UNITED STATES PATENT OFFICE.

WILLARD H. READ, OF TROY, NEW YORK.

DESIGN FOR A SCORE-BOARD.

47,422.

Specification for Design.

Patented June 8, 1915.

Application filed March 3, 1915. Serial No. 11,868. Term of patent 14 years.

To all whom it may concern:

Be it known that I, WILLARD H. READ, a citizen of the United States, residing at Troy, Rensselaer county, New York, have invented a new, original, and ornamental Design for Score-Boards, of which the following is a specification, reference being had to the accompanying drawing.

Figure 1 is a top plan view and Fig. 2 an

elevation of a score board, showing my new design.

I claim:

The ornamental design for a score board, as shown.

WILLARD H. READ.

Witnesses:

GEO. S. COOPER,
J. D. FITZPATRICK.
